SAFETY DEVICE

Wade H. Wineman, Michigan City, Ind., assignor to Sullivan Machinery Company, a corporation of Massachusetts

Application May 8, 1936, Serial No. 78,691

51 Claims. (Cl. 121—130)

My invention relates to safety devices, and more particularly to automatic shut-off devices for pressure fluid conducting means. From certain of its aspects, and in certain embodiments thereof, it relates to pumping mechanisms, and more particularly to automatic shut-off valves for use in connection with oil well pumping apparatus.

In connection with various fluid operated devices it is desirable, and, for economy, necessary, that automatic supply line control devices be provided in order to shut off fluid flow in the event of derangement or breakage of the devices supplied with pressure, so that the pressure supplied may not blow through the devices without control and result in burns or possible injury, if the fluid to be controlled is of a dangerous nature, and loss in any event.

Oil well pumping systems in which a central pressure fluid supply plant provides operating fluid for a number of expansible chamber pumping motors, particularly when such motors are of the fluid-operated valve type, afford a field in which there is especial advantage to and need for a device which will permit unhindered normal fluid supply at a regulated rate, but automatically interrupt fluid supply when an abnormal, higher rate of flow takes place.

In a very satisfactory form of oil well pumping apparatus of the character mentioned, a central compressor plant provides air at relatively high pressure to a number of different pumping units and takes in the used pumping fluid from these pumping units at a lower pressure, while there is maintained, through suitable control means, within the piping between the discharges of the units and the intake of the compressor, a substantial back pressure. Each pumping unit comprises a single acting pressure-fluid-operated pumping motor having automatically controlled admission and discharge valves governed by movement of the motor piston, and the motor piston is connected to a relatively long sucker rod line and by the latter to a pump plunger in an oil well. Because of the widely scattered positions of the pumps and the absence of an attendant at each pump, it is necessary to provide automatic control means which will prevent serious consequences in the event of derangement or breakage. Since the motor valves are of the automatic type, it is desirable to make provision which will preclude blowing of air directly through the motor cylinder from the relatively high pressure supply line to the considerably lower pressure discharge line should the valve

mechanism stick open. It is also desirable to insure shutting down of the pump in the event of sucker rod breakage.

It is an object of the present invention to provide an improved automatic flow-controlling device. It is another object of the invention to provide an improved automatic shut off valve controlled by the rate of fluid flow past it. It is a further object of the invention to provide an improved automatic shut off valve for pumping 10 motors in which the valve automatically moves toward closed position during the period of fluid supply to a pumping motor but does not attain closed position unless the motor operation is materially deranged. It is a still further object of 15 the invention to provide an improved automatic shut-off valve for pumping motors particularly of the fluid actuated valve type. It is yet another object of the invention to provide an improved motor and protective valve combination. It is a 20 still further object of the invention to provide an improved controlling mechanism particularly adapted for use in systems of the type hereinabove mentioned for guarding against the consequences of the derangements which were referred to. 25 It is a still further object of my invention to provide an improved automatic flow-controlling valve mechanism applicable, not only to a pumping system of the type described, but to any other use in which periodic control of flow is 30 necessary, but continuous flow is undesirable. It is yet a further object of the invention to provide an improved automatic control valve mechanism for a pumping motor adapted to permit normal operation thereof, but in the event 35 of flow through the valve mechanism materially longer than the time normally required for a single working stroke of the pump motor to shut down the pump motor entirely. Other objects and advantages of the invention will hereinafter 40 more fully appear.

In the accompanying drawings, in which there are shown for purposes of illustration two forms or embodiments which my invention may assume in practice, together with a detailed modification 45 of one of them,

Fig. 1 is a view mainly in side elevation but with some parts broken away and other parts omitted, of a portion of a pumping apparatus in which my improved controlling mechanism in one of its illustrative embodiments is incorporated.

Fig. 2 is a central section through the illustrative embodiment of Figs. 1 to 5.

Figs. 3 and 4 are vertical sections on the lines 3-3 and 4-4, respectively, of Fig. 2.

Fig. 5 is a fragmentary top view of the mechanism shown in Fig. 2.

5 Fig. 6 is a fragmentary view showing a modification of the species of Figs. 1 to 5.

Fig. 7 is a fragmentary view of a pumping system in which a modified embodiment of my invention is incorporated.

10 Fig. 8 is a central vertical section through the illustrative form of the control valve proper, shown in Fig. 7.

Referring to Figs. 1 to 5 and the mechanism therein disclosed, and particularly at first to Fig. 15 1, it will be noted that a pumping motor 11 is supported from the top member 12 of a frame 13 which is suitably supported, in a manner not shown, by a platform or derrick floor or the like, 14. Upon the platform is also mounted an 20 air-preheater 15, to which air under substantial pressure, say, of the order of 250 to 300 pounds, is supplied from a central compressor plant (not shown) through a supply line 16. The air passing through the preheater passes next through a stop 25 valve 17, and then a vent valve 18, and next an automatic controlling mechanism generally 30 designated 19, and then through a pipe 20 to the inlet side of the pumping motor 11. From the exhaust side of the pumping motor the spent air 35 is returned through a pipe 21, at a substantial back pressure, to the intake side of the compressor. The pumping motor 11 is provided with suitable automatically controlled admission valve mechanism 22 and exhaust valve mechanism 23, 40 and may be operated either with a certain amount of expansion or compression, or on a substantially rectangular cycle, in accordance with the adjustments thereof. It will suffice to say with respect to this motor, that with the piston 24 there- 45 of at the bottom of the cylinder 25, air is admitted through the admission valve mechanism and raises the piston; and that as the piston nears, or reaches (dependent upon the adjustment) the upper end of its stroke, the admission valve mech- 50 anism 22 closes off fluid supply beneath the piston. Shortly thereafter the exhaust valve mech- 55 anism 23 releases the pressure beneath the piston 24 to the exhaust line 21. The piston 24 is then moved downwardly by the weight of the sucker rod line 26, to which it is connected, and by the weight of the pump plunger (not shown), the rate of downward movement being retarded by the back pressure and by the quasi dash-pot action of the pump plunger. When the piston 24 approaches the bottom of its stroke, the ex- 60 haust valve is closed; closure of this valve taking place at the end of the stroke or somewhat before, depending upon the adjustment made in accordance with the desire to operate on the rectangular cycle or with compression. Sub- 65 substantially at the bottom of the down stroke of the piston, the admission valve mechanism 22 again effects supply of air beneath the piston, and the cycle is repeated. This motor makes a relatively small number of strokes a minute, 15 or 16 strokes being a not uncommon number. The motor shown is fully disclosed in Patent No. 2,004,146, granted June 11, 1935.

It will be evident that during the upward 70 stroke of the piston air flows in beneath the piston 24 and, assuming a relatively constant supply pressure of the air, and a relatively constant load against which the motor is operating, the rate of flow through the pipe 20 will have a relatively definite value. It will be evident, more-

over, that the period of flow will be rather definitely determined; in other words, it may be said that there will be periodic flows at a given rate through the pipe 20.

Now referring to the automatic controlling 5 mechanism, it will be observed that the mechanism 19 comprises a valve casing 30 having a connection at 31 through which fluid is admitted thereto from the preheater 15, and also having a connection 32 through which fluid passes to the 10 piping 20. The connection 31 opens into a chamber 33, and the connection 32 opens out of a chamber 34; and these chambers are separated by a double-walled septum 35 which has a chamber or flow passage 36 formed therein. The passage 36 is communicable with the chamber 33 through a port 37 surrounded by a valve seat 38. The chamber 36 communicates with the chamber 34 by a passage 39 whose lower end is surrounded by a valve seat 39a. The valve casing 20 also provides a cylindrical bore 40 in alignment with the passage 39, and of slightly greater diameter than the passage 39. Within the bore 40 a valve element 41 is slidably mounted. This valve element has a socket or recess 42 therein, in 25 which a valve stem 43 rests. The valve stem is loosely connected at its upper end with a form of dash-pot mechanism which includes a perforated piston element 44 having passages 44a therethrough, and an intermittent sealing 30 element 45 adapted to close passages 44a when in engagement with the member 44; the piston 44 slidably fitting in a cylindrical chamber 46 formed in the upper end of the casing 30. The space below the valve element 41 communicates 35 freely with the chamber 33, as at 48.

The upper part of the valve casing 30 contains a bore 49 whose axis is parallel to the bore of the chamber 46, and in alignment with the passage 37. Within this bore 49 a relatively heavy 40 valve body 50 is reciprocable. At its lower end the valve body 50 carries a valve member 51 which is adapted to seat upon the seat 38. The valve body 50 is not a tight fit for its bore, and accordingly pressure within the chamber 36 may be 45 transmitted to the space above the valve body. An adjustable stop member 53 limits the opening movement of the valve 51. If it is desired to provide a greater seating tendency than is furnished by the mere weight of the element 50, a 50 spring with suitable adjusting means could obviously be arranged, for example, as shown in Fig. 6, between the top of the member 50 and the upper end of the chamber 49. A suitable cover 54 supports the adjustable stop member 53 and closes the bores 46 and 49. A suitable lower cover member 55 closes the chamber 33 at a point in alignment with the bore 40.

From this description of the structure of the controlling mechanism 19, the mode of operation 60 can be readily understood. Flow of air through this mechanism is intermittent, as was pointed out above; for air flows through the mechanism only when the pump motor piston is on its up stroke, and the flow stops completely during the 65 time that the piston is on its down stroke. Air entering the casing 30 through the connection 31 has to lift the weighted valve 50, 51, and the weight of this valve is such as to cause a small difference in pressure to exist, during the time 70 flow through the casing 30 is taking place, between the pressure in the chamber 36 and that in the chamber 33. A difference of only one or two pounds per square inch is normally adequate.

Now assuming that the pressure is 250 pounds 75

in the chamber 33, and, during flow to raise the piston 24, 248 pounds in the chambers 36 and 34 and in the line 20, it will be noted that the upper surface of the valve element 41 will be subjected to a 248-pound pressure while the lower surface is subjected to a 250-pound pressure. This small difference in pressure tends to force the valve 41 upwardly towards its seat at the lower end of the passage 39, being more than adequate to lift the weight of parts 41, 43, 44 and 45. Upward movement of the valve 41 is retarded by the piston 44 to such an extent that the normal up-stroke of the pump piston 24 will be completed before the valve 41 can reach the upper end of its travel and seat.

When the up-stroke of the pump motor piston 24 is completed, flow of air through the valve stops, and the pressure on both sides of valves 51 and 41 will equalize, by reason of the fact that valve 41 is not a tight fit for its chamber or bore 40. With the pressure equal on both sides of the valve 41, the latter will drop to its bottom position.

The dash-pot piston 44 might tend to be retarded in its downward movement, but this is prevented by reason of the fact that as soon as the valve 41 drops away from contact with the stem 43, the latter is free to move downwardly and lower the sealing member 45 relative to the piston 44; and thereupon flow through the ports in the piston 44 will permit free downward movement of the dash-pot piston 44. By the time the down stroke of the piston 24 has been completed, the parts are again in the position shown in Fig. 2, and ready again to go through the cycle which has been described.

The cycle explained occurs with each stroke of the pump. Should the flow of air through the motor 11 become constant at any time—as through sticking of the distribution valves in open position, or any other derangement—the valve 41 would continue its upward movement until it seated, due to a difference in pressure caused by a continuous flow of such duration as to permit the valve 41 to complete its upward travel. When once closed, the valve 41 will remain closed until reopened intentionally, which may be done by closing the throttle 17 and opening the vent 18.

Should the sucker rods break, allowing the pump piston 24 to speed up on the up stroke, there would be an increased rapidity of the flow of air past the valve 51, which, due to the throttling occasioned by the limited opening of this valve when rapid flow is occurring, would cause a greater difference between the pressures in chambers 33 and 36. This additional pressure difference would be sufficient to increase the speed of movement of the valve 41 substantially and cause it to close and shut off the air to the pump.

60 It will be understood that the additional pressure drop will be quite substantial, since the adjusting screw 53 will be set to permit only the desired rate of flow for normal pumping operation, to occur through the port 31, without substantial throttling effect. A bypass 56 is provided, and this may, when it is desired to run the pump faster than its normal speed, for a short time, be made operative by opening a valve 57 to permit flow past the mechanism 19 at a more rapid rate than would be possible without closing the valve 41.

From the foregoing description it will be evident that I have provided an improved valve mechanism which is in some measure a governor valve, since any tendency to overspeed would be

checked by closing of the valve 41. Moreover, the valve 50, 51 controls the maximum flow rate. This mechanism as a whole is, however, of primary importance in that it prevents waste of air in the event of derangement of the pump mechanism, and in that it shuts down the pump and prevents serious damage in the event that any breakage of the sucker rod line or blowing through of pump packings takes place. 5

The use of the valve mechanism, including the 10
valve 50, 51, may be dispensed with, if this be
desired, and in the species of the invention, from
certain of its aspects, shown in Figs. 7 and 8,
the weighted valve and its function are omitted.
It will be noted that, as in the first form, a suitable 15
platform 61 supports a frame 62, from whose
top 63 a pressure fluid operated pumping motor
64 is suspended. The motor 64 has a fluid
controlled admission valve mechanism 65 and a fluid
controlled exhaust valve mechanism 66, and its
piston rod 67 is connected with a polished rod 68
of an oil well pump mechanism whose discharge
line 69 is arranged somewhat above the connection 10
20 for casing head gases. A central compressor
plant, not shown, which may supply air
at several hundred pounds pressure to a number
25 of different pumping motors is here also the
usual source of fluid supply. The supply line 71
conducts air from such a source at high pressure
to a preheater 72, and from the latter a line 73
30 conducts the heated high-pressure live fluid past
a stop valve 74, bleed valve 75, and an automatic
control or shut-off valve 76, to the admission
valve mechanism 65. Fluid is exhausted from the
motor 64 through the exhaust valve mechanism
35 66 at a substantial back pressure and returned
to the intake of the central compressor through
an exhaust fluid line 77. A by-pass 78 having a
suitable controlling valve 79 is arranged to permit
40 fluid to flow from the line 73 to the admission
valve mechanism 65 without passing through the
automatic control valve 76 whenever this may be
desirable for a short time. By reason of the
presence of a third stop valve 80, it is possible to
45 disconnect the automatic stop valve 76 completely
and still operate the pump, while repairs or ad-
justments are made or while cleaning the auto-
matic stop valve.

The valve mechanism 76 is adapted to permit the normal flow of air to the pump motor 64 without impediment. This means that the valve mechanism 76 is ineffective to interrupt fluid flow past it when such flow occurs at a constant rate during the pumping strokes of the motor and for the periods during which such flow occurs. Adjustment of the mechanism is possible so that the valve will not move at all during either the normal flow during the pumping strokes of the motor or during the brief rushes of air as the admission valve opens, and it is also possible to arrange and adjust the parts so that the valve will move gradually toward closed position during each flow of fluid past it but not attain closed position within the duration of the normal flow period during which admission to the pumping motor is taking place. In either case, the valve mechanism will operate upon a sustained rush of air at an excessive rate completely to interrupt fluid supply past it.

The valve mechanism 76 comprises a casing 70 and suitable valve and control devices within the casing for effecting the mode of operation mentioned. The casing is of composite construction, and includes a main body member 81 having a septum 82 dividing the interior thereof into an 75

admission space 83 and a discharge space 84. The septum is ported at 85. The other portion of the casing includes a member 86 having a depending ported cylindrical sleeve member 87 provided with packing means 88 adapted to form a seal with the wall of the port 85, said sleeve having a series of openings 89 to conduct fluid entering its interior from the admission chamber 83, into the discharge chamber 84. The depending sleeve 87 is supported upon a flange 90 which is adapted to be held by suitable screws 91 to the upper portion of the casing member 81. The casing member 86 supports, at its upper end, a cylinder portion 92 having a bore 93 and a head 94. The bore 93 slidably receives a dash-pot piston 95, and a by-pass passage 96 controlled by an adjustable throttling-screw 97, accessible by removal of a threaded plug 98, controls the by-passing of fluid from top to bottom of the dash-pot cylinder 92. Within the admission space there is mounted a sleeve 100 having a ported bottom portion 101 suitably connected at 102 to an adjusting screw 103. This sleeve 100 may be adjusted to a top-most position with its upper end in contact with the lower end of the sleeve portion 87. Under such circumstances, flow from the valve mechanism would obviously be impossible. By adjusting the screw 103 to move the sleeve 100 downwardly, a variable flow space may be provided between the top of the sleeve 100 and the bottom of the sleeve 87, and a differential in pressure between the space at the top of the former and the space at the bottom of the same may be produced. A desirable adjustment provides a difference in pressure of perhaps one-half pound per square inch. Within the sleeve 100, which provides a cylindrical bore 105 a piston 106 is slidably mounted. This piston is connected to a rod 107 which extends upwardly to a valve element 108 which cooperates with a valve seat 109 formed on the lower end of the dash-pot piston 95. Upward movement of the rod 107 causes the valve element 108 to push the dash-pot piston 95 upwardly. The dash-pot piston is traversed by a plurality of passages 110 lying within the compass of the valve seat 109 for the valve 108, so that upon separation of the valve 108 from its seat 109, flow may take place freely between the spaces at the opposite ends of the dash-pot piston. A suitable packing with a gland generally designated 113 is provided for the lower end of the member supporting the adjusting screw 103. The cylindrical neck portion 114 of the casing element 86 lying between the flange 90 and the bottom of the cylinder portion 92 is provided with a glassed inspection-port 115, and by observing the positions of the single ring 116 and of the double ring 117 and of the double-width ring 118 the position of the valve may be noted and proper adjustments readily determined. Piston 106 coacts with 87 as a valve.

When it is desired that the valve mechanism 76 shall not operate with any tendency to shut off flow through the valve casing 81, except upon a prolonged abnormal rush of fluid through the latter, adjustments can be made as by providing a relatively larger space between the top of the sleeve 100 and the bottom of the sleeve 87; and by obstructing, through the throttling screw 97, flow through the by-pass 96, moreover, there will be no or very little movement of the valve member 106 toward the lower end of the sleeve 87, during the normal flow of the fluid to the pumping motor which occurs during the admis-

sion periods of the latter. If desired, however, by somewhat restricting the flow area between the top of the sleeve 100 and the bottom of the sleeve 87, and by increasing to the necessary amount the freedom of flow through the by-pass passage 96, the valve 106 may be caused to move from its bottom position towards closed position, but not to such an extent as to restrict flow, during the normal admission periods of the pumping motor. It will be observed that virtually any adjustment may be accomplished within the desired range. Assuming, as that is the more complex situation, that an adjustment is made which causes the valve member 106 to move upwardly during each period of admission to the pumping motor, it will be observed that the valve element will be subjected during fluid flow to a greater pressure at its bottom through the passages 101 than acts upon its upper end. Upon the opening of the admission valve a rush of air will occur and the valve 106 will gradually begin to move upward, but its upward rate of movement will be retarded by the dash-pot 96, and it will not attain top-most position before cut-off occurs. It will be immediately released, from its upward moving tendency, upon equalization of the pressure at opposite sides of the valve mechanism 76, which occurs upon closing of the admission valve mechanism 65. The valve 106 will then fall away from the seat 109 and the valve 106 will drop immediately to its bottom-most position. The dash-pot piston 95 will promptly drop down also until it again engages the valve element 108, this being made possible by the openings 110 through the piston 115; and the parts will be ready for a new cycle.

From the description given, the mode of operation with other adjustments will be apparent, and it will be evident that I have provided improved means for controlling pressure fluid supply lines, which will enable normal unimpeded flow, and even permissible supernormal flows of brief duration, but which will close off pressure flow with certainty upon protracted excessive flow. It will be evident that this device also is simple, rugged, not easily deranged, adjustable to different desired conditions of operation, and thoroughly effective in operation. It will further be noted that the adjustment need not be altered during the cleaning of the device, for by removing the screws 91 the seat for the valve 106 which exists at the bottom of the sleeve 87 may be readily cleaned, and the upper portions of the device overhauled as may be desired without any interference with the adjustment of the valve mechanism per se. The dash-pot cylinder is placed so high as to eliminate to a large extent likelihood of access thereto of dirt or oil in the air flowing through the valve mechanism. When it is necessary to clean the apparatus, the by-pass previously described may be used to prevent the necessity for shutting down the pump.

While I have in this application specifically described two forms and a minor modification of one of them, which my invention in various aspects may assume in practice, it will be understood that these forms of the same are shown for purposes of illustration and that the invention may be further modified and embodied in various other forms without departing from its spirit or the scope of the appended claims.

This application is a continuation in part of my copending applications Serial No. 681,542, filed July 21, 1933 (now abandoned) and Serial

No. 746,171, filed Sept. 29, 1934, and also of my earlier application Serial No. 619,658, filed June 28, 1932, now abandoned of which Serial No. 746,171 is a continuation in part.

5 What I claim as new and desire to secure by Letters Patent is:

1. In a valve mechanism, a casing providing a passage, a plurality of valves in said casing each adapted to interrupt flow through said passage, means associated with one of said valves for producing a differential in pressure between the opposite sides of said valve during flow through said casing, and means governed by such differential in pressure and associated with the other of said valves whereby the same is caused to close after a predetermined period of uniform flow past the first mentioned valve.

2. In a valve mechanism, a casing providing a passage, a plurality of valves in said casing each adapted to interrupt flow through said passage, means associated with one of said valves for producing a differential in pressure between the opposite sides of said valve during flow through said casing, and means associated with the other of said valves for subjecting the same through-out flow through said casing to an uncounterbalanced closing force which is a function of the differential in pressure existing between the opposite sides of the first mentioned valve.

3. In a valve mechanism, in combination, a casing, parallel bores therein, valve seats coaxial with said bores, said casing having therein a supply passage leading to one of said seats, a passage leading from the other side of said seat to the other seat, and a delivery passage leading from the other side of said last mentioned seat, a weighted valve associated with the first mentioned one of said seats, and a valve responsive to the pressures in and having surfaces communicating directly with the supply passage and the second mentioned passage for controlling flow past the second mentioned valve seat of fluid passing through said second mentioned passage.

4. In a valve mechanism, in combination, a casing, parallel bores therein, valve seats coaxial with said bores, flow passages leading to one of said valve seats, connecting said valve seats, and leading from the other of said valve seats, respectively, a weighted valve associated with one of said valve seats, and an imperforate valve directly responsive to and movable by the differential in pressure between the supply passage and the space beyond the first mentioned valve for controlling flow past the second valve seat.

5. In a valve mechanism, in combination, a casing, parallel bores therein, valve seats coaxial with said bores, flow passages leading to one of said valve seats, connecting said valve seats, and leading from the other of said valve seats, respectively, a weighted valve associated with one of said valve seats, a valve responsive to pressure in the supply passage and in the space beyond the first mentioned valve for controlling flow past the second valve seat, said second mentioned valve having a wide range of movement without affecting flow through said casing, and dashpot means associated with said second mentioned valve for controlling the movement thereof.

6. In a valve mechanism, in combination, a casing, parallel bores therein, valve seats coaxial with said bores, flow passages leading to one of said valve seats, connecting said valve seats, and leading from the other of said valve seats, re-

spectively, a weighted valve associated with one of said valve seats, a valve responsive to pressure in the supply passage and in the space beyond the first mentioned valve for controlling flow past the second valve seat, said second mentioned valve having a wide range of movement without affecting flow through said casing, and dashpot means associated with said second mentioned valve for controlling the movement thereof, said dashpot means providing a uniform opposition to valve movement in a closing direction.

7. In combination, an expansible chamber motor, a load movable by said motor, and means for controlling the supply of motive fluid to said motor comprising means for regulating the rate of fluid supply to said motor to preclude excessive speed thereof during normal loaded operation including a valve for effecting different reductions in pressure in accordance with different rates of flow, and separate valve means controlled by such reductions in pressure and varying in operating speed in accordance therewith and moving substantially uniformly during any given reduction throughout the continuance thereof for automatically interrupting flow of fluid to said motor in the event said motor loses its load.

8. In combination, a motor including a cylinder having a piston movable therein, a load connected with said piston, fluid distribution means, and fluid supply means having controlling mechanism associated therewith including a valve device for limiting fluid supply to said motor to a rate adapted to the desired rate of loaded piston movement with a predetermined small drop in pressure below supply pressure, and means controlled by the drop in pressure beyond said valve device for automatically interrupting pressure supply to the piston and shutting down the motor until same is operator-restarted in the event of substantial exceeding of said rate of piston movement.

9. In a valve mechanism, in combination, a casing having a passage extending therethrough and traversing a plurality of valve seats, a valve arranged to cooperate with the valve seat first reached by fluid passing through said passage and having associated therewith means for producing a differential in pressure between opposite sides of said seat, and a second valve subjected on the opposite ends directly to and responsive to the pressures at opposite sides of the first valve seat for controlling flow past the second valve seat and biased towards closed position by the differences in such pressures.

10. In a valve mechanism, in combination, a casing having a passage extending therethrough and traversing a plurality of valve seats, a valve arranged to cooperate with the valve seat first reached by fluid passing through said passage and having associated therewith means for producing a differential in pressure between opposite sides of said seat, a second valve responsive to the pressures at opposite sides of the first valve seat for controlling flow past the second valve seat and having a substantial range of movement before affecting flow, and means associated with the second mentioned valve for controlling the movement thereof and providing substantially uniform regulation thereof irrespective of movement of said valve.

11. In a valve mechanism, in combination, a casing having a passage extending therethrough and traversing a plurality of valve seats, a valve arranged to cooperate with the valve seat first reached by fluid passing through said passage and

- having associated therewith means for producing a differential in pressure between opposite sides of said seat, a second valve responsive to the pressures at opposite sides of the first valve seat 5 for controlling flow past the second valve seat and having a substantial range of movement before affecting such flow, and means associated with the second mentioned valve for controlling the movement thereof in a closing direction only 10 and providing a substantially uniform resistance to closing movement throughout valve movement.
12. In a valve mechanism, in combination, a casing having a passage extending therethrough and traversing a plurality of valve seats, a valve 15 arranged to cooperate with the valve seat first reached by fluid passing through said passage and having associated therewith means for producing a differential in pressure between opposite sides of said seat, an imperforate second valve responsive to and movable by the differential between 20 the pressures at opposite sides of the first valve seat for controlling flow past the second valve seat, and retarding means associated with the second mentioned valve for controlling the movement thereof in a closing direction only. 25
13. In a valve mechanism, in combination, a casing having a passage extending therethrough and traversing a plurality of valve seats, a valve arranged to cooperate with the valve seat first 30 reached by fluid passing through said passage and having associated therewith means for producing a differential in pressure between opposite sides of said seat, a second valve responsive to the pressures at opposite sides of the first valve 35 seat and movable to control flow past the second valve seat, and dash-pot means associated with the second mentioned valve for retarding but not interrupting movement thereof.
14. In a valve mechanism, in combination, a 40 casing having a passage extending therethrough and traversing a plurality of valve seats, a valve arranged to cooperate with the valve seat first reached by fluid passing through said passage and having associated therewith means for producing a differential in pressure between opposite 45 sides of said seat, an imperforate second valve responsive to the pressures at opposite sides of the first valve seat for controlling flow past the second valve seat, and dash-pot means associated with the second mentioned valve for controlling the movement thereof. 50
15. In a valve mechanism, in combination, a casing having a passage extending therethrough and traversing a plurality of valve seats, a valve 55 arranged to cooperate with the valve seat first reached by fluid passing through said passage and having associated therewith means for producing a differential in pressure between opposite sides of said seat, a second valve responsive to the pressures at opposite sides of the first valve seat for controlling flow past the second valve seat, and dash-pot means associated with the second mentioned valve for controlling the movement thereof in a closing direction only. 60
16. In a valve mechanism, in combination, a 65 casing having a passage extending therethrough and traversing a plurality of valve seats, a valve arranged to cooperate with the valve seat first reached by fluid passing through said passage 70 and having associated therewith means for producing a differential in pressure between opposite sides of said seat, a second valve responsive to the pressures at opposite sides of the first valve seat for controlling flow past the second valve seat, and dash-pot means associated with the 75

second mentioned valve for controlling the movement thereof in a closing direction only, said dash-pot means providing a time delay in the closing movement of said valve slightly exceeding the normal periods of flow through said 5 5

17. In combination, a motor comprising admission and exhaust valve mechanisms and a pressure fluid movable element, a load movable by said element, and means for controlling the 10 supply of motive fluid to said motor comprising means for regulating the rate of fluid supply to said motor to preclude excessive speed thereof during normal loaded operation, and pressure fluid operated means controlled by pressure conditions beyond 15 said regulating means and having a substantially uniform rate of closing movement during normal load movement by said motor for automatically interrupting flow of fluid to said motor in the event said motor loses its load. 20

18. In combination, a motor comprising admission and exhaust valve mechanisms, a load movable by said motor, and means for controlling the supply of motive fluid to said motor comprising weighted valve means for regulating the 25 rate of fluid supply to said motor to preclude excessive speed thereof during normal loaded operation, and pressure fluid operated means controlled by pressure conditions beyond 30 said weighted valve means and having a substantially uniform rate of closing movement during normal load movement by said motor for automatically interrupting flow of fluid to said motor in the event said motor loses its load. 35

19. In combination, in a valve mechanism, a 40 casing providing a valve seat, a valve movable towards said seat, means for subjecting the opposite sides of said valve to a differential pressure during flow through said casing whereby said valve approaches said seat at a substantially 45 uniform rate while flow through said casing occurs at a uniform rate, and means for resisting the movement of said valve towards its seat operative to permit substantially unimpeded movement of said valve in the opposite direction. 50

20. In combination, a motor including a cylinder, distributing valve mechanism, a piston, and fluid supply and exhaust means for said motor, and means for automatically controlling fluid supply to said motor including a valve device 55 automatically moved in a direction to interrupt fluid supply to said motor during and throughout each admission of fluid to said motor, and means for controlling the rate of movement of said valve to preclude interruption of fluid supply during 60 normal motor operation.

21. In combination, a motor including a cylinder, distributing valve mechanism, a piston, and fluid supply and exhaust means for said motor, and means for automatically controlling 65 fluid supply to said motor including a valve device automatically moved in a direction to interrupt fluid supply to said motor during a large part of each admission of fluid to said motor and having a quick return movement during 70 motor exhausting, and means for controlling the rate of movement of said valve to preclude interruption of fluid supply during normal motor operation.

22. In combination, a motor comprising a 75 cylinder having a piston reciprocable therein, and means for supplying operating fluid to said motor at a controlled rate including a supply line having a controlling valve therein governed by the rate of fluid flow to said motor and mov- 80

ing towards closed position during each admission of fluid to said motor but constrained during normal motor operation to a rate of movement precluding complete closing prior to completion of admission to said motor.

23. In combination, a motor comprising a cylinder having a piston reciprocable therein, and means for supplying operating fluid to said motor at a controlled rate including a supply line having a controlling valve therein, means for imparting to said valve automatically during working piston movement a force tending to close the valve and effective to produce valve movement in a closing direction, and means for controlling movement of said valve by such force precluding during normal motor operation complete closing of said valve prior to completion of admission to said motor.

24. In combination, a motor comprising a cylinder having a piston reciprocable therein, and controlling means for said motor including a valve for controlling the supply of working fluid to said motor, and means for causing said valve to pass through a cycle of movement each time the motor performs a working cycle, said valve cycle including a movement in a closing direction during each working stroke of the motor and a movement in an opening direction intermediate successive working strokes of the motor, said valve having automatic means associated therewith for retarding the movement whereby it traverses the first portion of its cycle more slowly than the motor traverses the corresponding portion of its cycle, whereby closing of said valve prior to the completion of the working stroke of said motor, during normal operation, does not take place.

25. In combination, a motor comprising a cylinder having a piston reciprocable therein, and controlling means for said motor including a valve for controlling the supply of working fluid to said motor, and means controlled during the working stroke of the piston by the rate of piston movement for causing said valve to pass through a cycle of movement each time the motor performs a working cycle, said valve cycle including a movement in a closing direction during each working stroke of the motor and a movement in an opening direction intermediate successive working strokes of the motor, said valve having automatic means associated therewith for retarding its movements whereby it traverses the first portion of its cycle more slowly than the motor traverses the corresponding portion of its cycle, whereby closing of said valve prior to the completion of the working stroke of said motor, during normal operation, does not take place.

26. In combination, a motor comprising a cylinder having a piston reciprocable therein, and controlling means for said motor including a valve for controlling the supply of working fluid to said motor, and means governed during the working piston stroke by the fluid passing to said motor for causing said valve to pass through a cycle of movement each time the motor performs a working cycle, said valve cycle including a movement in a closing direction during each working stroke of the motor and a movement in an opening direction intermediate successive working strokes of the motor, said valve having automatic means associated therewith for retarding its movements whereby it traverses the first portion of its cycle more slowly than the motor traverses the corresponding portion of its cycle, whereby closing of said valve prior to the completion of

the working stroke of said motor, during normal operation, does not take place.

27. In combination, a valve casing having supply and discharge chambers, a valve for controlling communication between said chambers, means for creating a differential pressure varying directly with the rate of flow from said discharge chamber and subjecting said valve thereto in a closing direction, said differential pressure adapted to impart slow movement in a closing direction to said valve even during the normal intended flow between said chambers, and pressure fluid means for preventing closure of said valve upon but momentary increases in such differential pressure.

28. In combination, a valve casing having supply and discharge chambers, a valve for controlling communication between said chambers, said valve movable upwardly to interrupt such communication and normally suspended in open position, means for creating a differential pressure varying directly with the rate of flow from said discharge chamber and subjecting said valve thereto in a closing direction, said differential pressure adapted to impart slow movement in a closing direction to said valve even during the normal intended flow between said chambers, and pressure fluid means for preventing closure of said valve upon but momentary increases in such differential pressure.

29. In combination, a valve casing having supply and discharge chambers, a valve for controlling communication between said chambers disposed, in the absence of flow between said chambers, in full-open position and having a substantial range of movement in a closing direction before affecting freedom of flow between said chambers, means for creating a differential pressure varying directly with the rate of flow from said discharge chamber and subjecting said valve thereto in a closing direction, said differential pressure adapted to impart slow movement in a closing direction to said valve even during the normal intended flow between said chambers, and means cooperating with said valve to preclude closure thereof during the first occurrence of an abnormal pressure drop in said discharge chamber and operative to permit substantially un retarded valve movement towards open position from a partially closed position.

30. In combination, a valve casing having supply and discharge chambers, a valve for controlling communication between said chambers, means for creating a differential pressure varying directly with the rate of flow from said discharge chamber and subjecting said valve thereto in a closing direction, said differential pressure adapted to impart slow movement in a closing direction to said valve even during the normal intended flow between said chambers, and means including a one-way fluid dash-pot cooperating with said valve to preclude closure thereof during the first occurrence of an abnormal pressure drop in said discharge chamber.

31. In combination, a valve casing having supply and discharge chambers, a valve for controlling communication between said chambers and free to move from open to closed position and having substantial movement in a closing direction during which it leaves communication between said chambers unaffected, means for subjecting said valve to a closing force upon an abnormal increase in flow from said discharge chamber, and unidirectionally acting fluid means for limiting the rate of valve movement during

- the initial period of increased flow and so maintaining said valve short of a position in which it will restrict communication between said chambers, during such initial period.
5. 32. In combination, a valve casing having supply and discharge chambers, a valve for controlling communication between said chambers and free to move from open to closed position and having substantial movement in a closing direction during which it leaves communication between said chambers unaffected, means including a continuously open communication with the supply chamber for subjecting said valve to a closing force upon an abnormal increase in flow from said discharge chamber, and means arranged to oppose the movement of said valve by the pressure variations effected upon flow variation, for limiting the rate of valve closure and precluding said closing force from affecting communication between said chambers during the initial period of increased flow but permitting valve closure upon sustained increased flow.
10. 33. In combination, a valve casing having supply and discharge chambers, a port connecting said chambers and surrounded by a valve seat, a valve arranged to cooperate with said seat, a piston having a one-way attachment to said valve, means for subjecting opposite sides of said piston to pressure conditions in said discharge chamber delaying the communication of variations in pressure to one side of the piston, and means including a continuously open communication with the supply chamber for subjecting said valve to a differential closing pressure.
15. 34. In combination, a valve casing having supply and discharge chambers, a port connecting said chambers and surrounded by a valve seat, a valve arranged to cooperate with said seat, and means for maintaining said valve open during brief variations in pressure between said chambers but operative to permit movement thereof gradually towards closed position and effective automatically to effect closure of said valve upon substantial continued drop in pressure in said discharge chamber including a piston attached to said valve, means for subjecting opposite sides of said piston to pressure conditions in said discharge chamber delaying the communication of variations in pressure to one side of the piston, and means for subjecting said valve to a differential closing pressure including a continuously open communication with the supply chamber and means for shielding said valve from the direct rush of fluid through said port.
20. 35. In combination, a valve casing having supply and discharge spaces separated by a ported wall, a valve arranged in the supply space for cooperation with the port in said wall, and means for effecting automatic closure of said valve upon a sustained substantial reduction in pressure in said discharge space but precluding instantaneous closure of said valve though permitting immediate movement thereof upon the occurrence of a substantial reduction in such pressure including a cylinder formed in said valve casing and aligned with the port in said wall, a valve-connected piston in said cylinder, and means for connecting one end of said cylinder directly with the discharge space and providing for the other end thereof a restricted connection with the discharge space.
25. 36. In combination, a valve casing having supply and discharge spaces separated by a ported wall, a valve arranged in the supply space for cooperation with the port in said wall, and means for effecting automatic closure of said valve upon a sustained substantial reduction in pressure in said discharge space but precluding instantaneous closure of said valve upon the occurrence of a substantial reduction in such pressure including a sleeve open at both ends and surrounding said valve, a piston connected with said valve, a cylinder at the discharge side of the ported wall and receiving said piston, and means for connecting one end of said cylinder directly with the discharge space and providing for the other end thereof an adjustably restricted connection with the discharge space.
30. 37. In combination, a valve casing having supply and discharge spaces separated by a ported wall, a valve arranged in the supply space for cooperation with the port in said wall, and means for effecting automatic closure of said valve upon a sustained substantial reduction in pressure in said discharge space but precluding instantaneous closure of said valve upon the occurrence of a substantial reduction in such pressure, including means for shielding said valve from direct action of the flowing fluid while subjecting it at all times during flow therethrough to supply-side pressure in a closing direction and to the pressure at the port in said wall in the opposite direction, and means at the discharge side of the ported seat for maintaining said valve open during normal pressure differences between said supply and discharge spaces and during momentary increases of such differences but operative to permit closure on substantial occurrences of such increased pressure differences.
35. 38. In combination, a line constantly supplied with pressure fluid, a line for conducting fluid from said first mentioned line, automatic means for connecting said lines normally operative to establish repeated connections for relatively short periods with intermediate flow interruptions, and a valve mechanism also controlling flow between said lines and including a valve for closing communication between said lines, means associated with said valve for moving the same when normal flow between said lines is taking place in a closing direction, and regulating means for the closing movement of said valve effective to limit its rate of movement so that closing thereof during normal flow periods is precluded though said valve moves in a closing direction, but ineffective to prevent closure of said valve on occurrence of abnormally protracted flow.
40. 39. In combination, a line constantly supplied with pressure fluid, a line for conducting fluid from said first mentioned line, automatic means for connecting said lines normally operative to establish repeated connections for relatively short periods with intermediate flow interruptions, and a valve mechanism also controlling flow between said lines and including a valve for closing communication between said lines, means associated with said valve for moving the same when normal flow between said lines is taking place in a closing direction, and regulating means for the closing movement of said valve effective to limit its rate of movement so that closing thereof during normal flow periods is precluded though said valve moves in a closing direction, but ineffective to prevent closure of said valve on occurrence of abnormally high flow.
45. 40. In combination, a valve casing having supply and discharge spaces separated by a ported wall, a valve arranged in the supply space for cooperation with the port in said wall, a sleeve in the supply space having a bore of uniform cross

section for receiving said valve and open at its top and surrounding the valve and permitting continuous access of supply space pressure to the surface of said valve remote from the port, and 5 means for yieldingly retarding closing movements of said valve.

41. In combination, a valve casing having supply and discharge spaces separated by a ported wall, a valve arranged in the supply space for cooperation with the port in said wall, a sleeve in the supply space open at its top and surrounding the valve and providing a stationary guide for the latter and permitting continuous access of supply space pressure to the surface of said valve 15 remote from the port, and a fluid dashpot for retarding valve movements.

42. In combination, a valve casing having supply and discharge spaces separated by a ported wall, a valve arranged in the supply space for cooperation with the port in said wall, a sleeve in the supply space open at its top and surrounding the valve and providing a stationary guide for the latter and permitting continuous access of supply space pressure to the surface of said 25 valve remote from the port, and a dashpot at the discharge side of said port for retarding valve movements only in a closing direction.

43. In combination, a valve casing having supply and discharge spaces separated by a ported 30 wall, a valve arranged in the supply space for cooperation with the port in said wall, an axially adjustable sleeve in the supply space open at its top and surrounding the valve and permitting access of pressure to the surface of said valve remote from the port, and means for yieldingly 35 retarding closing movements of said valve.

44. In combination, a source of operating fluid, a fluid motor having a cylinder and fluid distributing means for said cylinder for controlling motive fluid supply and exhaust including exhaust 40 controlling means and structurally distinct, relatively movable, valve means controlling admission and cut off, said valve means having actuating means for causing the same to effect admission of fluid from said source and after an interval to cut off the admission of fluid from 45 said source, and controlling valve means for interrupting communication between said cylinder and said source in the event said first mentioned valve means fails to effect cut-off within a pre-determined time after admission occurs and exhaust and admission become concurrent.

45. In combination, a source of operating fluid, a fluid motor having a cylinder and fluid distributing means for said cylinder including valve 50 means controlling admission and cut off and having actuating means for causing the same to effect admission of fluid from said source and after an interval to cut off the admission of fluid from said source, and controlling valve means for interrupting communication between said cylinder and said source in the event said first mentioned valve means fails to effect cut-off within a pre-determined time after admission occurs, said last 55 mentioned valve means including a valve element having operating means moving it in a closing direction during each period of admission.

46. In combination, a source of operating fluid, a fluid motor having a cylinder and fluid distributing means for said cylinder including valve 60 means controlling admission and cut off and having actuating means for causing the same to effect admission of fluid from said source and after an interval to cut off the admission of fluid from 65 said source, and controlling valve means for

interrupting communication between said cylinder and said source in the event said first mentioned valve means fails to effect cut-off within a predetermined time after admission occurs, said last mentioned valve means including a valve element having operating means moving it towards closed position during each period of admission but at a rate less than sufficient to effect closure during a normal period of admission to said 70 motor.

47. In combination, a source of operating fluid, a fluid motor having a cylinder and fluid distributing means for said cylinder including valve means controlling admission and cut off and having actuating means for causing the same to effect admission of fluid from said source and after an interval to cut off the admission of fluid from 75 said source, and controlling valve means for interrupting communication between said cylinder and said source in the event said first mentioned valve means fails to effect cut-off within a predetermined time after admission occurs, said last mentioned valve means including a valve element having a relatively long range of movement in a closing direction and throttling flow only after a substantial portion of such range has been completed and having operating means for moving it in a closing direction during each 80 period of admission.

48. In combination, a valve casing having supply and discharge chambers, a valve for controlling communication between said chambers, said valve in the absence of flow between said chambers normally in a position in which it is without effect on rate of flow and having a substantial 85 movement in a closing direction before affecting materially the rate of flow from said discharge chamber, means for creating a differential pressure varying directly with the rate of flow from said discharge chamber and subjecting said valve 90 thereto in a closing direction, said differential pressure adapted to impart slow movement in a closing direction to said valve even during the normal intended flow between said chambers, and pressure fluid means for preventing closure of 95 said valve upon but momentary increases in such differential pressure.

49. In combination, a valve casing having supply and discharge chambers, passage means connecting said chambers, a valve movable to interrupt communication between said chambers, means for supporting said valve, when there is no flow between said chambers, in a position in which said passage means is completely unobstructed by said valve and from which position 55 said valve has a substantial travel in a closing direction before commencing to obstruct said passage means, means for creating a differential pressure varying with the rate of flow through said passage means and subjecting said valve 60 thereto in a closing direction, and means for opposing a resistance to the closing movement of said valve varying with the rate of closing movement, said differential pressure during periods of normal flow between said chambers sufficient to 65 overcome the resistance opposed at a relatively low speed of valve movement by said means for opposing closing movement of said valve, whereby said valve moves at a slow rate and for a substantial period in flow-obstructing direction, before obstructing said passage means, upon the initiation of normal flow between said chambers.

50. A system of the class wherein a source of motive fluid is recurrently connected through a valve mechanism with a pressure fluid motor 75

cylinder for periods corresponding to the normal periods of admission to said motor and in which the motor is normally under a load adapted to preclude wide fluctuations in the rate of motive fluid supply thereto and in which valve devices are provided for cutting off motive fluid supply to the motor in the event of loss of the motor load, characterized by the fact that said valve devices include a valve movable to a position to 5 cut off motive fluid supply to the motor and having associated therewith means for creating a pressure differential during such periods of connection, means for subjecting said valve thereto,

and means for opposing the effect thereof on said valve, said several means providing a resultant force adapted to effect a relatively slow closing movement of said valve throughout each normal period of admission to the motor.

51. A system as defined in claim 50, characterized by the fact that the valve which is movable to a position to cut off motive fluid supply to the motor has such a range of movement, prior to materially affecting flow, that during normal 10 loaded operation of the motor said valve does not affect the fluid supply to the latter.
